UNITED STATES PATENT OFFICE.

DAVID A. BEERY AND NATHANIEL B. SPRAGUE, OF SPRINGFIELD, OHIO.

APPARATUS FOR MAKING FIRE-KINDLERS.

SPECIFICATION forming part of Letters Patent No. 284,597, dated September 11, 1883.

Application filed March 6, 1883. (No model.)

To all whom it may concern:

Be it known that we, DAVID A. BEERY and NATHANIEL B. SPRAGUE, citizens of the United States, residing at Springfield, in the county of Clarke and State of Ohio, have invented certain new and useful Improvements in Machines for Making Fire-Kindlers; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Our invention relates to improvements in machines for making fire-kindlers.

Our invention relates more particularly to the auxiliary devices connected with the press for forming fire-kindlers made of a composition of sawdust, rosin, &c.

The object of our invention is to facilitate the process of manufacture in discharging the kindlers from the molds by causing the upper dies to be automatically elevated or withdrawn 25 from the lower section of the same, thus freeing the kindlers instantaneously from pressure and allowing them to be easily and quickly discharged from the molds; also, to provide means for easily removing the molds from under the press by mounting the frame upon a sliding platform carried upon a track, whereby the operation of filling the molds, pressing the kindlers, and removing the lower section containing them and discharging them from 30 the same is accelerated.

Figure 1 is a top view of our improved press-machine for making fire-kindlers. Fig. 2 is a vertical section of the same on line *x*. Fig. 3 is a front elevation in section through 40 line *y*, Fig. 2. Fig. 4 is a view of the under side of the platform-slide.

The machine consists of a frame-work of timbers, supporting a platform or table, *a*, which forms the bed for the molds. On this 45 platform are fastened two parallel rails, *c*, which extend from the front of the platform to the rear, or nearly so, being turned upward at the ends to form stops for the sliding bed *b*, upon which the lower or matrix mold is placed. This bed consists of a broad plank 50 of oak, (or it may be of cast-iron,) provided on its under side with the projecting right-angled

guides *b' b'*, of which there are two at either side, as seen in Fig. 2, and in the detail view, Fig. 4. This bed plate or plank has a transverse slot or hand-hole at the front end, by which it is drawn out from under the following-block *e* of the press. Block *e* is square in its general outline, and is made thick enough to withstand the pressure given by the operation of the lever *h* and the cam *i*, which latter has its bearing upon the block *e*. Cam *i* is cast in one piece with its axle *i'* and its arm *k*. The axle *i'* is pivoted at either end in plates upon the standards *g* of the frame, which extend above the platform, upon either side, and are connected by a cross-beam above. The lever *h* is fastened upon the arm *k* of the cam by a pair of stirrup-irons, *l*, being made adjustable in its length by means of them.

The following-block *e* is suspended above the mold upon the four guide-posts *f*, which extend up through each of its corners, by the pressure of the spiral springs *f*, (there being one around each post,) extending from the bottom to the top of the same. The posts *f* are cylindrical, and the following-block *e* slides easily up and down upon them, but is kept at the top of the posts when released from the pressure of the lever, as seen in Figs. 2 and 3. Upon the under side of the block *e* is fastened the upper section or counterpart, *n'*, of the molds, which fits into the lower section, *n*, when pressed down over the cores of the dies. A portion of the dies is shown in Figs. 1 and 85 2. These have star-shaped cores, and are fully shown in the former patent of D. A. Beery, February 15, 1881, No. 237,804, on fire-kindler molds.

In operating the machine the lower section, 90 *n*, is first filled with the kindler composition, and it is placed upon the slide *b*, which has previously been drawn out to the front stop, *d*, of the rails *c*. After being placed thereon it is pushed back under the following-block *e* 95 until the rear guide-blocks strike the stops *d'* at the back ends of the rails, when it is in position to receive the upper section of the mold, which is pressed down by the lever and cam to the required degree. As soon as the pressure is removed the following-block *e*, with the upper dies, is automatically elevated, and the latter withdrawn from the lower ones by the action of the springs *l*, which push the follow-

ing-block back to the top of the posts *f*, thus releasing the lower section of the mold, which contains the pressed kindlers, and allowing it to be removed and discharged, as before stated.

5 We are aware that the cam-lever and sliding platform have been before used in printing-presses, &c., and we do not therefore claim them as our invention; but the specific arrangement of the parts and their application
10 for the purpose described we believe to be new; therefore

We claim as our invention—

The combination, with cam *i*, cast with its

axle *i'* and arm *k* in a single piece, the standards *g*, and the platform *a*, having parallel 15 rails *c*, of the automatically-separable molds, the removable bed-plate, and the sliding track and its bearing-rails, substantially as set forth.

In testimony whereof we affix our signatures in presence of two witnesses.

DAVID A. BEERY.
NATHANIEL B. SPRAGUE.
